UNITED STATES PATENT OFFICE.

ROBERT H. MUELLER, OF DECATUR, ILLINOIS, ASSIGNOR TO ADOLPH MUELLER,
TRUSTEE, OF DECATUR, ILLINOIS.

LAUNDRY-TUB FAUCET.

Application filed October 17, 1925. Serial No. 63,194.

The present invention relates to improvements in laundry tub faucets, particularly of that character in which a swinging nozzle is provided so that the faucet may deliver water to either tub of a two-tub fixture.

One of the objects of the invention is to provide a means for supporting the faucet which will not require the employment of special attaching means on the faucet body.

10 Heretofore it has been proposed to mount a faucet on a laundry tub by means of legs which required that the faucet body be provided with special lugs or attaching means for engagement therewith.

15 By the present invention, however, a support is provided which is adapted to engage the ordinary connection between the faucet outlet and swinging nozzle and which may be used with ordinary faucet bodies instead 20 of requiring a special form of such body to engage the supporting devices.

In the drawings:

Figure 1 is a plan of an embodiment of the invention as applied to a laundry tray 25 comprising two tubs or compartments.

Figure 2 is an elevation of the parts shown in Figure 1 with the foot portions of the supporting yoke shown in section.

30 Figure 3 is an end elevation. Figure 4 is a view similar to Figure 3, but showing the faucet support in reversed position.

35 Figure 5 is a section through the connection between the swinging nozzle and faucet outlet and the means of engaging the support therewith.

In the several figures of the drawing corresponding parts are designated by the same reference characters.

40 Referring to the drawing, 1 designates the rear wall of a laundry tray which is shown as being of the type having two tubs or compartments separated by a vertical division wall 2.

45 The particular form of faucet illustrated comprises a relatively elongated body 3 having suitable inlets with which connect hot and cold water supply pipes 4, 5, respectively, and a common outlet 6, with which is connected a swinging nozzle 7.

Flow through the faucet is controlled by valves connected with handles 8, 8, in the usual manner.

50 As the invention is adapted for use with various forms of faucet, it is not necessary

to describe more in detail the particular embodiment illustrated.

The faucet is supported from the rear wall 1 of the laundry tubs by a yoke shaped support which has an eye or passage formed in 60 its head member 9, through which the connection between the faucet outlet 6 and the swinging nozzle 7 passes.

The downwardly diverging legs 10 of the yoke shaped support are shaped to embrace the upper edge of the wall 1 of the tubs, and each is secured in position on said wall by a set screw 11. As shown, one of the lugs or jaws 12 of each foot of the supporting yoke is substantially in the vertical plane of one 70 edge of such yoke, while the other coacting jaw or clamp member 13 is offset to a considerable extent from the yoke, being connected therewith by a horizontal member 14.

75 By this particular arrangement of clamp-jaws the faucet may be readily positioned in substantial vertical alignment with the inner or outer edge of the rear wall of the tub. As shown in Figure 3, the faucet is arranged in substantial alignment with the inner edge of the tub wall and the offset jaw 13 engages the outer face of such wall. However, as shown in Figure 4, the position of the yoke with respect to the tub may be readily reversed, the offset jaw 13 being positioned against the inner face of the tub wall and thereby the body of the faucet will be supported in substantial alignment with the rear edge of the tub.

80 In either of the two positions of the support just referred to the connection thereof with the faucet is not varied. Under both conditions the faucet is supported centrally by the yoke, the eye or passage in the head 9 receiving the connection between the faucet outlet 6 and swinging nozzle 7 at all times.

85 While it will be evident that the present invention does not involve any particular connection between the swinging nozzle and faucet, there is illustrated in Figure 5 a 100 form of connection which has been found to be very suitable. Such connection comprises a tube 16, which is threaded into the outlet 6 of the faucet and depends therefrom, passing through the eye in the head 9 of the supporting yoke. Into said sleeve extends a tube 17 having a flange about its inner end which abuts a shoulder formed in the tube 16. A plug 18 is threaded into the tube 16 about the tube 17 and compresses a suitable 105 110

packing 19. The lower end of the tube 17 which extends beyond the plug 18 is connected by a suitable threaded joint with the nozzle 7.

- 5 If desired, a set screw 20 may be provided in the rear face of the head member 9 of the yoke, which screw will engage the tube 16 of the outlet connection and effect a rigid connection between the faucet and yoke.
- 10 It is believed that the advantages of the invention will be readily appreciated from the foregoing description and the drawing. It will be seen that there is provided a very simple means for supporting an ordinary faucet from a laundry tub, and that it is not necessary to provide any special means on the faucet body, and supplemental to the connection between its outlet and the swinging nozzle, for engaging the support. In the
- 15 drawings many of the parts are shown more
- 20

or less diagrammatically, and it is to be understood that there can be variation from the exact details shown without departing from the invention.

I claim:

The combination with a faucet having an outlet passage extending downward from its body and a swinging nozzle communicating with said passage, of means for supporting the faucet from a tub comprising a body surrounding and adapted to be rotated to a limited extent relative to the outlet passage of the nozzle, and two diverging leg members formed integral with said body and each having its free end bifurcated to receive the edge of a tub wall.

In testimony whereof I have hereunto set my hand.

ROBERT H. MUELLER.
